DRAWER STRUCTURE

Florence S. Knoll, New York, and Vincent J. Cafiero, Hartsdale, N.Y., assignors to Knoll Associates, Inc., New York, N.Y., a corporation of New York
Filed Sept. 21, 1960, Ser. No. 57,566
4 Claims. (Cl. 312—234.1)

This invention relates to drawer structure and particularly to a drawer head. In the preferred embodiment described herein, the drawer head incorporates a novel unitary structure which includes novel means for retaining an index and a novel drawer pull.

A file drawer is normally provided with a head having a flat front face, means attached to the drawer head for holding an index to designate the contents of the drawer, and a pull for opening and closing the drawer. In the typical drawer head of the prior art, the pull consists of a forwardly projecting handle and a forwardly projecting frame is provided for holding the index. The disadvantages of the conventional apparatus just described are that the projecting handle and the index frame are subject to accidental engagement with persons or articles passing, with resulting possible injury, either to the passing persons or articles or to the handle or index frame. Furthermore, the index card, being external to the face of the drawer, and usually externally inserted into the frame, is subject to accidental disfigurement or dislodgment by passing persons or objects.

These and other disadvantages are eliminated, in accordance with the present invention, by the use of recesses in the flat face of the drawer head to retain the index and to provide a pull or hand grip for opening the drawer. A file cabinet having drawers constructed in accordance with the present invention has smaller overall dimensions, and hence requires less floor space, than a conventional cabinet. In a large array of cabinets, the space saved may be of substantial importance.

An object of this invention is to provide an improved head for a drawer such as a file cabinet drawer.

Another object of this invention is to provide new and improved means for retaining an index on the face of a drawer.

A further object is to provide new and improved pull means for opening a drawer.

A further object is to provide a file drawer head having a recess to hold an index.

A further object is to provide a drawer head having a recess to provide means for opening and closing the drawer.

A further object is to provide a drawer head of the type described in which an index retaining recess and a pull defining recess are both incorporated into a unitary structure.

The foregoing and other objects of the invention are attained in the drawer structure described herein. That drawer has a head structure formed of two spaced walls, each wall consisting of a sheet steel stamping, the two walls having interfitting peripheral flanges by which they are frictionally held together to form the head. The drawer head is made somewhat thicker than conventional sheet metal drawer heads, i.e., the spacing between the walls is greater. The front wall of the drawer head is provided near its top with a horizontal elongated aperture. Located in the aperture and between the two walls is a unitary casting including a frame portion having a shoulder which closely fits against the edge of the aperture in the front wall. A septum divides the casting into two sections, one of which serves as a part of the index holder, and the other as the drawer pull. Both sections of the casting have rearwardly extending members which

2

abut the rear wall of the drawer head. These rearwardly extending members have downwardly depending lugs threaded to receive machine screws which extend through openings in the rear wall. A backing plate is mounted on the casting behind the index holding portion thereof and provides a background support for the inserted index member. One end of the plate abuts against the septum, so that that end of the index holding recess is closed. The other end of the index holding recess is opened and is aligned with an opening in the edge of the drawer head, through which an index card may be inserted into the index holding recess.

Other objects and advantages of my invention will become apparent from a consideration of the following specification and claims, taken together with the accompanying drawings.

In the drawing:

FIG. 1 is a front elevational view of a drawer head embodying the invention;

FIG. 2 is a side elevational view of a drawer including the head of FIG. 1;

FIG. 3 is a perspective view of a casting which forms a principal part of the index receiving recess and the drawer pull recess;

FIG. 4 is a sectional view taken on the line IV—IV of FIG. 1, looking in the direction of the arrows;

FIG. 5 is a sectional view taken on the line V—V of FIG. 1, looking in the direction of the arrows;

FIG. 6 is a sectional view taken on the line VI—VI of FIG. 1, looking in the direction of the arrows; and

FIG. 7 is a sectional view similar to FIG. 5, but illustrating a modification.

There is shown in the drawings a drawer head including a front wall 1 and a rear wall 2. The walls 1 and 2 are formed in a conventional manner, of sheet steel stampings, with interfitting flanges 1a and 2a (see FIG. 4) attached in any suitable fashion to the side walls 3 of the drawer. The front wall 1 is provided near its upper end with a horizontally elongated rectangular aperture 1b. Inside the aperture 1b is mounted a casting 4, best seen in FIG. 3, having a rib 5 projecting forwardly from its front face and closely fitting inside the aperture 1b. The casting 4 has a flat surface 4a abutting the inside surface of the wall 1 at the periphery of aperture 1b. The rib 5 of casting 4 provides a frame for the two apertures. The casting 4 is separated by a septum 6 into an index receiving portion 7 and a drawer pull portion 8 (see FIG. 3).

The index receiving portion 7 includes a horizontally elongated lower rail 9 and a horizontally elongated upper rail 10, connected at their respective ends by the septum 6 and by a vertical end rail 11.

The drawer pull portion 8 includes a lower rail 12 and an upper rail 13, both elongated and extending horizontally, and connected at their ends by the septum 6 and a vertical end rail 14.

The rib 5 extends along the entire periphery of the casting 4, including particularly the rails 10, 13, 14, 12, 9 and 11.

A projection 16 extends rearwardly from the lower rail 9 at a point near its left-hand end, as viewed in FIG. 3 and terminates in a downwardly depending lug 17 having a threaded aperture to receive a screw 18 extending through an opening in the inner wall 2 of the drawer head.

A backing plate 19 (see FIG. 5), which may be a sheet metal stamping, has a rearwardly projecting flange 19a at its lower edge, which flange is adapted for attachment to the projection 16 and to another projection 20 by means of suitable screws 21. The upper edge of the plate 19 has a forwardly projecting flange 19b whose

forward edge is bent downwardly, as shown at 19c so as to define a channel which receives the upper edge of the rail 10. A surface 10a along the rail 10 is set back from the surface 4a to allow space for the flange portion 19c.

The right-hand end of the plate 19 abuts against the septum 6, as shown in FIG. 4. The corner of the plate 19 at the flange 19a engages shoulders formed at the connection of the projections 16 and 20 with the rail 9. The casting 4 and the plate 19 thus provide a receptacle for receiving an index member such as a card or sign. The receptacle is closed at its back, top, bottom and inner ends. The receptacle is open at its left end or outer end, as shown at 22 in FIG. 4. This open end is aligned with an aperture 23 formed in the flange 1a at the lateral edge of the front wall 1, so that the card or index member can be slipped through the aperture 23 into the open end 22 of the index receptacle, thereby bringing it into alignment with a sight opening 7a defined by the index receiving portion 7 of the casting 4.

The index receiving portion 7 of the casting 4 forms a frame around the sight opening 7a. The recess which receives the index card or other member extends beyond the frame except at the end defined by the septum 6. This overhang of the frame retains the index card in its recess and prevents it from moving forwardly out of the recess.

The drawer pull portion 8 of the casting 4 is best seen in FIGS. 3, 4 and 6. Referring to FIG. 6, it may be seen that the rails 12 and 13 have vertically extending portions 12a, 13a, which are generally parallel to the front wall member 1. The portions 12a, 13a extend vertically a short distance from the pull opening 8a and join rearwardly horizontally extending portions 12b and 13b, which preferably extend back to and abut the inner wall 2. The inwardly extending portion 12b is provided with two downwardly dependent lugs 24 provided with threaded holes for receiving screws 25 inserted through the inner wall 2. The horizontal extensions 12b and 13b thus serve as spacers between the front and rear walls 1 and 2.

To pull the drawer out, the fingers may be inserted through the opening 8a, with the palm of the hand either upward or downward. If the palm is upward, the fingers readily grip the surface portion 13a to pull the drawer outward. If the palm is downward, the fingers readily grip the surface of portion 12a. In the case of the upper drawer of a file cabinet, it is usually most convenient for a person to reach in with the palm downward and grip the surface 12a. In the case of the lower drawer, it is more convenient to have the palm upward and grip the surface 13a. The intermediate drawers of a filing cabinet may be gripped in either fashion. It may be seen that the structure shown is suitable for filing drawers at any level, by virtue of its convenience for gripping either with the palm upward or downward.

There is shown in FIG. 7 a modified form of index retaining structure, which may be used in place of the plate 19 of FIG. 5. In FIG. 7, a casting 26 corresponds generally to the index retaining portion 7 of the casting 4 of FIGS. 3 to 5. An L-shaped sheet metal member 27 has a flange 27a riveted to the inner wall 2 of the drawer head and a forwardly projecting flange 27b extending between the inner wall 2 and a groove 26a formed in the back of a casting 26, just below the sight opening in the index member. Another sheet metal stamping 28, of a generally channel shaped cross-section, has a lower horizontally extending flange riveted to the flange 27b and an upper horizontally extending flange riveted to the top flange 2a of the inner wall 2. The index retaining receptacle is defined between the casting 26 and the sheet metal stamping 28. As in the case of the index retaining receptacle in FIG. 5, its outer end is open, so that the index card may be slipped through an opening 23 in the edge of the drawer head.

While we have shown and described certain preferred embodiments of our invention, other modifications thereof will readily occur to those skilled in the art, and we therefore intend our invention to be limited only by the appended claims.

We claim as our invention:

1. A file drawer comprising a drawer head, said head including spaced outer and inner walls, said outer wall being flat and having a horizontally elongated aperture therein and a combined drawer pull and index supporting means mounted between said walls and including a frame extending around the periphery of the aperture and abutting the inner side of said outer wall, a vertical septum extending transversely of the frame between the inner and outer walls and separating a drawer pull portion of said frame from an index retaining portion thereof, said drawer pull portion comprising a grip member having upper and lower surfaces extending along the upper and lower edges respectively of the elongated aperture and covering said edges, said upper surface extending vertically upward along the inside of said outer wall and then horizontally across to said inner wall to provide an upper finger grip, said lower surface extending vertically downward along the inside of said outer wall and then horizontally across to said inner wall to provide a lower finger grip, said index retaining portion including means for holding an index in a position visible from outside the outer wall, said index supporting means being open at one end to permit the insertion of an index into said means.

2. A file drawer comprising a drawer head, said head including spaced inner and outer walls, said outer wall being flat and having a horizontally elongated aperture therein, a unitary frame in one integral piece extending around the periphery of said aperture and abutting the inner side of the outer wall, spacer means at each end of the frame including inwardly extending projections integral with the frame extending between the frame and the inner wall and attached to the inner wall, upper and lower grip members integral with opposed upper and lower portions of the frame and adjacent one end of the frame, said grip members extending along the inner surface of the outer wall and cooperating with the frame to provide upper and lower finger grips within the drawer head for pulling the drawer out, and a backing plate spaced laterally from the grip members and between said inner wall and another portion of the frame adjacent the other end of the frame, said backing plate and said another portion of the frame cooperating to define a receptacle within the drawer head and adapted to receive an index.

3. A file drawer comprising a drawer head, said head including spaced inner and outer walls, said outer wall being flat and having a horizontally elongated aperture therein, a unitary frame in one integral piece extending around the periphery of said aperture and abutting the inner side of the outer wall, spacer means at each end of the frame, the spacer means for said one end of the frame including inwardly extending projections integral with the frame extending between the frame and the inner wall and attached to the inner wall and the spacer means for said other end of the frame comprising a horizontally extending angle member having horizontal flange and a vertical flange, said vertical flange having a surface abutting and attached to said inner wall and said horizontal flange having an edge abutting said frame, upper and lower grip members integral with opposed upper and lower portions of the frame and adjacent one end of the frame, said grip members extending along the inner surface of the outer wall and cooperating with the frame to provide upper and lower finger grips within the drawer head for pulling the drawer out, and a backing plate spaced laterally from the grip members and between said inner wall and another portion of the frame adjacent the other end of the frame, said backing plate and said another portion of the frame cooperating to define a receptacle within the drawer head and adapted to receive an index.

4. A file drawer comprising a drawer head, said head including spaced outer and inner walls, said outer wall being flat and having a horizontally elongated aperture therein and a combined drawer pull and index supporting means including a peripheral frame and a transverse frame member separating a drawer pull portion of said frame from an index retaining portion thereof, said drawer pull portion comprising upper and lower frame portions extending along the upper and lower edges respectively of the elongated aperture, said upper portion cooperating with said outer wall and the aperture therein to provide a recess extending vertically upward along the inside of said outer wall for use as an upper finger grip, said lower portion cooperating with said outer wall and the aperture therein to provide a recess extending vertically downward along the inside of said outer wall for use as a lower finger

grip, said index retaining portion including means for holding an index in a position visible from outside the outer wall.
